UNITED STATES PATENT OFFICE

ROY A. CLARK, OF VANCOUVER, BRITISH COLUMBIA, CANADA

SHINGLE-FINISHING MACHINE

Application filed December 27, 1927. Serial No. 242,821.

This invention relates to a method of smoothing or dressing the sides or flat surfaces of wooden shingles, and also the butts or thick end edges of same, in order to produce a smooth and finished surface for painting or decorative pattern purposes. This is effected by a mechanism which carries the shingles in a direction transverse or perpendicular to the grain of the wood against rotating cutters, these latter being set in their correct relative position to produce a smooth and uniformly shaped or tapered section without any tendency to split or break the shingles during the operation.

These objects are attained by the mechanism illustrated in the accompanying drawings, of which:

Fig. 1 is a side view with the shingle depositing belt, bearings and rollers removed, in order to show the feed roll driving mechanism.

Fig. 2 is a sectional plan taken on the line 7—7 in Fig. 1 and thus supposing the top plate, top bearings and top belt drive removed, in order to show the relative position of the pick-up roller, feed rolls and cutters, and the pads or supports for the shingles while passing through or against the cutters.

Fig. 3 is a sectional end view taken on the line 8—8 in Fig. 1 showing the vertical and tilted rolls and the method of varying the speed of the chain feed.

Fig. 4 shows an enlarged view of the chain, indicating one of the pawls or specially shaped projecting links which engage with the edges of the shingles and carry them towards the pick-up rolls.

Fig. 5 is an enlarged view of the top belt drive by which the pick-up rolls are driven from the chain shaft at the same peripheral speed as the chain.

Fig. 6 is an enlarged view of the shingle depositing mechanism showing the method of delivery of the shingles by belt to the moving chain and the engagement of the projections on the chains with the nearest layer of shingles.

Similar numerals refer to similar parts throughout the several views.

Referring to the drawings:—

The shingles are deposited upon a moving band or belt 9 running upon rollers, and are placed upright thereon with the butts down and the flat sides perpendicular to the direction of motion of the belt. The belt is wide enough to take the width of an ordinary bundle of shingles, the shingles in each bundle having been previously separated from each other, and all the butts turned to the same end of the bundle.

The shingles are then placed upon the belt in layers the width of the original bundle, the first layer being laid, or carried by the belt, up against the stop bars 10, the lower one of which is close to the belt 9 and forms a shelf upon which the shingles are carried by the belt. These stop bars keep the shingle from contact with the plain portion of the moving chains 11 and they remain stationary upon the shelf until picked up by the projecting pawls 12 on the chains and thus carried toward the pick-up rolls 13 and 14.

The function of the pick-up rolls 13 is to carry the shingle forward to the feed rolls 15 and 16. The pick-up rolls 13 are shown driven by a belt or band 17 from the chain shaft 18. The pick-up rolls 14 are mounted in sliding bearings 19 controlled by springs by which the rolls are pressed up against the shingles passing through, but can give or adjust themselves to shingles of varying thickness, and keep the shingles in contact with the rolls 13.

The feed rolls 15 are geared together to run at the same peripheral speed, and are driven by the shafts 20 and 21 and suitable gearing from the belt speed cone 22. The feed rolls 16 are also mounted in sliding bearings 19 by which they can adjust themselves to shingles of varying thickness, and press them up against the feed rolls 15, the function of which is to carry the shingles forward between the vertical pads 23 and 24 to the side cutters 25 and 26 which dress the sides of each shingle as it passes through, the butts being dressed by the butt cutter 27 underneath during the passage of the shingles. The vertical pad 23 extends the full height of the shingle and supports it against the action of the cutter 100.

26, the shingle being steadied by the pressure of the vertical spring pad 24. When passing the cutter 25 the shingle is similarly steadied by the pad 28, and passing by the roll 29 is discharged at the end of the machine finished.

5 In order to provide for the fact that the layer of shingles in the width of the bundle may vary and be made up of several narrow shingles, and that consequently there may be 10 a variable proportion of the width taken up by gaps or distances between the edges of contiguous shingles, the speed of the chain drive is made easily variable by means of the friction wheels 30 and 31 by which the 15 motion is transmitted to the chain shaft 18 from the belt speed cone 22.

The variation is effected by means of the 20 lever 32 and thus the transverse shingle speed can be increased so that the shingles can catch up to those passing through the feed rolls 15 and 16 to the side cutters 25 and 26. The shingle being actually dressed by the side 25 cutters is pushed through by the shingle behind driven forward by the feed rolls 15. The belt drive 17 is shown enlarged in Fig. 5 and is so proportioned that the peripheral speed of the chain 11 and the pick-up rolls 13 is the same, and both speeds are varied together by the friction drive 30—31.

30 The feed rolls 15 are gear driven independently of this friction drive and rotate at a constant speed except as varied by changing the belt upon the speed cone pulley 22.

The side cutters 25 and 26 and the butt 35 cutter 27 are driven independently by belts or other suitable means.

In order to prevent the shingles from being carried forward in bunches to the roller 13 a fixed stop 33 is provided at a distance 40 from the chain 11 great enough to allow one shingle only when in contact with the chain drive to pass under it and thus prevent the overlying shingles from being also swept off the belt 9 by friction from the shingles in 45 contact with the pawls 12 on the chain 11 as they travel toward the roller 13.

Having now fully described my invention, what I claim and desire to be protected in by Letters Patent, is:

50 1. In a shingle finishing machine the combination with rotary cutters carried by a framework and revolvable by suitable gearing and characterized by substantially vertical spindles carrying said cutters, a belt 55 adapted to support and traverse a series of shingles butts downward on said belt, right-angular supporting means on said framework whereby said shingles are presented in true alignment with said cutters, a driving 60 chain with spaced apart projecting tabs, the said tabs being adapted to engage the edge of some of said shingles whereby the motion of said chain is imparted to said shingles.

65 2. In a shingle finishing machine the combination comprising, a framework or hous-

ing, rotary cutters on substantially vertical spindles supported in said housing, a movable table for stacking and delivering shingles to the machine and comprising a broad substantially horizontal but inclined belt, 70 pulleys supporting and propelling said belt, right-angular supporting means on said framework whereby shingles stacked vertically butts downwards with their sides adjacent and their edges adjacent on said belt may be correctly aligned for traverse and presentation to said cutters, a vertical shaft carrying sprocket wheels, driving chains engaging said wheels, projecting members at 75 spaced intervals on said chains and adapted to engage the edge of some of said shingles whereby a number of said shingles are traversed in the direction of said cutters, guiding and engaging means adapted to receive said shingles in their traverse to said cutters, 80 means whereby the speed of said guiding and engaging means may be varied to take up and accommodate itself to a varying amount of space separating the said shingles in their traverse from said belt, means for driving said cutters independently of said machine and means for driving said machine.

In testimony whereof I affix my signature.
ROY A. CLARK.
